UNITED STATES PATENT OFFICE.

JAMES D. LONER, OF ALABAMA CITY, ALABAMA, ASSIGNOR TO DRAPER COMPANY.
OF HOPE DALE, MASSACHUSETTS, A CORPORATION OF MAINE.

BOBBIN-STRIPPING DEVICE.

1,119,705.

Specification of Letters Patent.

Patented Dec. 1, 1914.

Application filed May 9, 1913. Serial No. 766,466.

To all whom it may concern:

Be it known that I, JAMES D. LONER, a citizen of the United States, and resident of Alabama City, county of Etowah, State of Alabama, have invented an Improvement in Bobbin-Stripping Devices, of which the following description, in connection with the accompanying drawing, is a specification, like characters on the drawing representing like parts.

This invention has for its object the production of a simple, efficient and rapid means for stripping the waste yarn from the bobbins removed, discharged or ejected from the shuttle in a loom provided with filling replenishing mechanism; and the object is to provide a device of this character which will entirely and completely remove the waste yarn, leaving the bobbin clean and without injuring or roughening the surface of the bobbin itself.

The invention involves features of construction and operation by which these desired results are practically secured, and which will appear more fully from the accompanying description and drawings and will be completely pointed out in the claims.

The drawings show a preferred form of mechanism embodying the invention.

In the drawings: Figure 1 is a side elevation of a machine embodying the invention. Fig. 2 is an enlarged detail chiefly in vertical cross section of the end of the plunger and its support. Fig. 3 is an end elevation looking toward the right of Fig. 1 of the upper portion of the machine. Fig. 4 is an end elevation of the upper portion of the machine partially in cross section and looking toward the right of Fig. 1. Fig. 5 is a detail in vertical cross section of the portion of the bobbin carrier indicating the position of the bobbin therein.

The machine comprises a suitable supporting frame herein shown as comprising the base 1, the bed-plate 2 and suitable standards 3 by which the bed-plate is supported from and above the base. An upright standard 4 rigid with the frame work projects upwardly above the bed-plate at one end and carries the bearing hub 5 in which is rigidly mounted a stud 6 projecting back parallel with the bed-plate. A rotary bobbin carrier is provided and journaled on the stud 6. This bobbin carrier comprises a disk-like head 7 and is provided

at equal intervals about its periphery with bobbin butt supports. In the construction illustrated these butt supports are simple notches 8 extending inwardly from the periphery of the disk and of a size just sufficient to receive the butts of the bobbins. The bobbins when in place project from the head 7 parallel with the axes of rotation of the bobbin carrier.

The bobbins are maintained in their parallel position during rotation by a support for the tips of the bobbins. This support is shown as a disk 9 rigidly secured by nuts to the projecting end of the stud 6 and this disk is of such diameter that when the tips of the bobbins rest thereon during the rotation of the bobbin carrier, the bobbins will remain substantially parallel with the axes of rotation of the carrier. The bobbin tip supporting disk 8 is provided at the bottom or opposite the plunger to be described, with a notch 10 to allow the passage of the plunger therewith.

A stripper for removing the waste yarn from the bobbin is mounted on the rotary carrier adjacent of the butt supports and embraces the barrel of the bobbin. Each stripper comprises a pair of stripper jaws 11 pivoted at 12 and 13 respectively near their ends to the head 7 of the carrier, and yieldingly pressed together as by the spring 14. The meeting line of these jaws extends radially of the bobbin carrier, and a pin 15 is provided for limiting the movement of the jaws toward each other. At their free ends the jaws are beveled inwardly toward each other as indicated at 16, and on their face are provided with curved notches 17 together adapted to surround partially and under the influence of the spring 14 to grip yieldingly the bobbin barrel. The construction is such that the axes of the notches align with the axes of the bobbin when in place in the butt support 8.

Suitable mechanism is provided for giving an intermittent rotation to the rotary bobbin carrier to bring it opposite the plunger to be described, which in this construction is located at the lowermost point of travel of the carrier. In the construction shown a ratchet 18 is provided at the rear of the head 7 and rigid therewith, and there is one tooth in the ratchet for each bobbin support on the carrier. A vertical reciprocating pawl carrying rod 19 is mounted

adjacent the ratchet 18. A pawl 20 is pivotally mounted on the pawl carrier 19 and held up against the ratchet 18 by a spring 21, so that upon each reciprocation of the 5 pawl carrier 19 the bobbin carrier is rotated one step thus successively bringing the bobbin supports and the bobbin supported therein to the lowermost position and opposite the notch 10 in the tip support 9. The 10 pawl carrier 19 is pivoted at its lower end to a lever 22, fulcrumed at 23 and held by a spring 24 against an eccentric 25 on a shaft 26 driven from any suitable source of power. Thus upon the rotation of the shaft the 15 pawl is given its actuated movement to rotate the bobbin carrier intermittently.

The rotary position of the bobbin carrier at each step is accurately defined and the bobbin carrier is locked at the conclusion of 20 its rotary movement by suitable mechanism. In the construction illustrated a spring arm 27 mounted on the bed-plate carries at its free end a head 28 adapted to spring and fit into the mouth of the butt supporting notches 8. A cam member 29 is mounted on the pawl carrier 19 and has its inclined or cam end so arranged that when the pawl carrier moves upward it forces the head 28 outwardly and frees the bobbin carrier to 30 rotation. During the rotation of the bobbin carrier between successive positions the head 28 rides on the periphery of the disk 7 and drops into the next notch 8. The device thus presents a spring positioning lock 35 defining and locating the position of the bobbin carrier at each step of its movement, and locking it in position while the stripping operation is being performed.

The plunger mechanism already referred 40 to is so located as to bring the plunger in line with the axis of the bobbin to be stripped when the bobbin upon the rotation of the bobbin carrier reaches the stripping position which is herein shown as the lowermost point of rotation. The plunger mechanism as illustrated comprises a plunger 30 mounted in bearings 31 on the bed-plate 2 and alined with the bobbin when in position to be stripped. The plunger is reduced at 45 its forward end as shown at 32 and has slidingly mounted on its extreme forward end a cup shaped head 33. In the form illustrated this head is keyed to the reduced portion of the plunger, a set screw 34 entering a 55 key slot in the plunger. A washer 35 is mounted on the reduced portion 32 and a coiled spring 36 surrounds the reduced portion 32 abutting against the body of the plunger and the washer 35 and thus holding 60 the cup shaped head 33 at the extreme end of the plunger as illustrated in Fig. 2. A standard 37 is mounted on the bed-plate in front of the forward bearing 31 and has an aperture 38 of sufficient size to permit the 65 plunger 30 to pass freely therethrough, but

to prevent the passage of the washer 35 so that as the plunger moves away from the bobbin carrier this standard 37 will check the movement of the washer 35 and cause the head 33 to be moved to the extreme end of the plunger, that is, to take the position shown in Fig. 2.

The plunger is given a reciprocating movement by means of a lever 39 having a slotted engagement at 40 with the plunger and pivoted at 41 to the standard on the base. This lever is retracted by the coiled spring 42 and moved forward by the cam 43 on the shaft 26. The cam 29 and the eccentric 25 are so timed that each time the bobbin reaches the lowermost or bobbin stripping position and comes in line with the plunger the plunger moves forward to perform the stripping operation.

The machine is operated preferably by power on the shaft 26 and attended by an operative who takes the bobbins with the waste thereon and places them in the carrier. This is done by pressing the butts of the bobbins into the butt supporting notches 8. In this movement the bobbin barrel sliding down on the cam surface 16 of the jaws forces the jaws apart and the barrel of the bobbin enters the opening formed by the notches 17. The jaws thus serve to hold the 95 bobbin in place and surround or embrace the bobbin barrel directly behind the waste to be removed. This may be seen in the sectional view in Fig. 5 where the waste 44 is indicated on the bobbin barrel 45. The 100 apertured or notched portion of the jaws is brought down to the edge 46. The tips of the bobbin are pressed against the edge of the tip supporting disk 9. The bobbins are put in place preferably during a pause in 105 the rotation of the bobbin carrier. As the bobbin carrier continues its rotation the bobbins are carried around until they reach the lowermost or stripping position opposite the plunger 30 and beneath the notch 10 in the tip supporting disk. Thereupon the plunger is actuated, the cup shaped head 33 rides on to the tip of the bobbin and if the bobbin is at all out of alinement brings it into alinement and centers it. The tip of the bobbin 110 then rests against the extreme end of the plunger and as the plunger continues its forward movement the bobbin is forced through the stripper jaws which yieldingly grip the barrel and as the movement is continued the waste is stripped along the barrel. As the bobbin is thus forced outwardly through the bobbin carrier the head 33 finally comes in contact with the bobbin carrier and its movement ceases. Thereupon the plunger continues its movement and the reduced end portion 32 forces the bobbin entirely out past the bobbin carrier head 7 and the stripped bobbin slides down the chute 47 into a suitable receptacle. As the plunger 115

returns the waste falls into the chute 48 located beneath the carrier and passes into another suitable receptacle. If any yarn is caught by the jaws or bobbin carrier, it is taken care of by a clearing device which seizes the yarn and removes it from the bobbin carrier. This device is shown as a rotating head 49 provided with a roughened surface such as a covering of card clothing and located adjacent to the bobbin carrier. In the construction illustrated the head 49 is carried by a shaft 50 mounted in a bracket 51 secured to one of the standards 3 and this shaft 50 is driven by a belt 52 running over a pulley 53 on the shaft 26.

It will thus be seen that the machine is entirely automatic. The only thing required of the operative being to position the bobbins in the bobbin carrier. The bobbins stripped clean pass into one receptacle and the waste into a separate receptacle. The waste is confined and held by the head 33 until it is dropped into the chute 48, and any yarn clinging to the rotary carrier is cleared by the roughened head 49. The operation is continuous and the bobbins are stripped with great facility and thoroughness. A box 54 may be provided in the bed-plate adjacent the bobbin carrier for holding a supply of bobbins to be stripped.

Having fully described my invention, what I claim as new and desire to secure by Letters Patent is:

1. A machine for stripping bobbins comprising a rotary bobbin carrier, a plurality of bobbin butt supports thereon, a plurality of strippers thereon, a plunger, and means for giving a relative longitudinal movement to said plunger and each of said supports as they are brought opposite each other by the rotation of the carrier whereby the bobbin is passed through the strippers and the waste thereon removed.

2. A machine for stripping bobbins comprising a rotary bobbin carrier, a plurality of bobbin butt supports located equi-distantly about the carrier periphery, a stripper mounted on the carrier adjacent each of said supports to embrace the bobbin barrel, a plunger means for intermittently rotating the carrier successively to bring each bobbin supported therein opposite the plunger, and means for giving a relative longitudinal movement to said plunger and carrier as they come opposite each other.

3. A machine for stripping bobbins comprising a rotary bobbin carrier, a plurality of bobbin butt supports located equi-distantly about the carrier periphery, a pair of stripper jaws yieldingly pressed together adapted to surround partially and to grip yieldingly the bobbin barrel and mounted on said carrier adjacent each of said supports, a plunger, means for intermittently rotating the carrier successively to bring

each bobbin supported therein opposite the plunger, and means for giving a relative longitudinal movement to said plunger and carrier as they come opposite each other.

4. A machine for stripping bobbins comprising a rotary disk carrier, a series of bobbin strippers and supports located equi-distantly about the carrier periphery, a single plunger device, means for automatically and intermittently rotating said carrier to bring successively the bobbins supported thereon opposite said plunger device and means for locking said carrier against rotation when each bobbin supported thereon arrives opposite said plunger.

5. A machine for stripping bobbins comprising a rotary disk carrier, a series of bobbin strippers and supports located equi-distantly about the carrier periphery, a single plunger device, means for automatically and intermittently rotating said carrier to bring successively the bobbins supported thereon opposite said plunger device, means for locking the said carrier against rotation when each bobbin supported thereon arrives opposite said plunger, and a support for the bobbin tips to maintain the axial direction thereof during the rotation of the carrier.

6. A machine for stripping bobbins comprising a rotary disk carrier, a series of bobbin strippers and supports located equi-distantly about the carrier periphery, a single plunger device, means for automatically and intermittently rotating said carrier to bring successively the bobbins supported thereon opposite said plunger device, means for locking said carrier against rotation when each bobbin supported thereon arrives opposite said plunger and a fixed annular support located parallel to and concentric with the said carrier to guide the bobbin tips and maintain the axial direction of the bobbins during the rotation of the carrier.

7. A machine for stripping bobbins comprising a rotary bobbin carrier, a series of pairs of stripper jaws arranged at equal intervals preferably on said carrier, springs for yieldingly drawing the jaws of each pair together, openings through said carrier in line with the jaw opening of each stripper pair, and means acting as each pair of stripper jaws comes opposite in the rotation of the carrier to force the bobbin through said jaws stripping the waste therefrom and through said carrier, ejecting the bobbin at the rear of the carrier and thus separating the waste and bobbins.

8. A machine for stripping bobbins comprising a pair of stripper jaws yieldingly pressed together and adapted to surround partially and to grip yieldingly the bobbin barrel, a device to contact with the tip of the bobbin, means to give a positive relative longitudinal movement to said pair of strip-

per jaws and said device to cause the waste on the bobbin to be stripped from the base toward the tip, and resilient means to give a yielding relative longitudinal movement 8 in the opposite direction to said pair of stripper jaws and said device to restore said parts to initial position.

9. A machine for stripping bobbins comprising a rotary bobbin carrier, a plurality 10 of bobbin butt supports thereon, a plurality of strippers thereon, a plunger, means for operating said plunger to force each bobbin as it comes opposite said plunger through the strippers and ejecting it from the carrier 15 with the waste stripper therefrom, and a pawl and ratchet mechanism for giving an intermittent rotary movement to said carrier.

10. A machine for stripping bobbins comprising a rotary bobbin carrier, a plurality 20 of bobbin butt supports thereon, a plurality of strippers thereon, a plunger, means for operating said plunger to force each bobbin as it comes opposite said plunger through 25 the strippers and eject it from the carrier with the waste stripped therefrom, a pawl and ratchet mechanism for giving an intermittent rotary movement to said carrier and a spring positioning lock for holding the 30 bobbin carrier in position at the end of each intermittent movement and during the stripping movement of the plunger.

11. A machine for stripping bobbins comprising a rotary bobbin carrier, a plurality 35 of bobbin butt supports thereon, a plurality of yielding stripper jaws located in line with each butt support, a plunger, a cup

shaped head slidingly mounted at the end of the plunger and adapted to engage the bobbin carrier while allowing the continued 40 movement of the plunger whereby as a bobbin comes opposite the plunger it will be alined by the cup shaped head and ejected through the bobbin carrier by the plunger moving through and with respect to said 45 head.

12. A machine for stripping bobbins comprising a bobbin carrier, an opening therein to receive a bobbin butt, a pair of yielding jaws mounted on said carrier with the 50 jaw openings in line with the butt supporting opening, the said jaws yieldingly embracing and gripping the bobbin barrel, a plunger alined with said jaw and butt supporting openings, a cup shaped head slidily mounted on the end of the plunger and held projected by a spring, means for reciprocating the plunger whereby upon the movement of the plunger toward the carrier the head would engage and center the 55 bobbin tip and upon the continued movement of the plunger the head will engage the bobbin carrier and pause while the end of the plunger will force the bobbin through the jaws and carrier, removing the waste 60 therefrom.

In testimony whereof, I have signed my name to this specification in the presence of two subscribing witnesses.

JAMES D. LONER.

Witnesses:

B. L. TURNER,
W. E. CLARK.

It is hereby certified that in Letters Patent No. 1,119,705, granted December 1, 1914, upon the application of James D. Loner, of Alabama City, Alabama, for an improvement in "Bobbin-Stripping Devices," an error appears in the printed specification requiring correction as follows: Page 4, line 15, for the word "stripper" read *stripped*; and that the said Letters Patent should be read with this correction therein that the same may conform to the record of the case in the Patent Office.

Signed and sealed this 5th day of January, A. D., 1915.

[SEAL.]

R. F. WHITEHEAD,
Acting Commissioner of Patents.
